UNITED STATES PATENT OFFICE.

GEORGE P. FARMER, OF NEW YORK, N. Y.

DESIGN FOR BUTTON-CARD.

SPECIFICATION forming part of Design No. 11,671, dated March 9, 1880.

Application filed June 27, 1879. Term of patent 7 years.

To all whom it may concern:

Be it known that I, GEORGE P. FARMER, of New York city, New York, have produced or invented a new and original Design for a 5 Button-Card, of which the following is a specification.

My design for a button-card is fully illustrated in the accompanying drawing; and it consists of a card on which are a number of 10 pictures of gloves, arranged as shown, buttons being attached to each picture of a glove in the positions which they usually occupy on the actual glove.

The pictures of the gloves are arranged in 15 rows, three of one row being in a position the reverse of those of the other row, as shown.

While the relative position of the pictures

of the rows is maintained, there may be but two pictures or more than three in each row on each card.

20

I claim—

The design for a button-card, said design consisting of pictures of gloves arranged in reversed rows in respect to each other, in the manner illustrated and described, and having 25 buttons arranged on the pictures, as set forth.

In testimony whereof I have signed my name to this specification in the presence of two subscribing witnesses.

GEORGE P. FARMER.
